UNITED STATES PATENT OFFICE.

JOHN J. HOVE, OF MINNEAPOLIS, MINNESOTA, ASSIGNOR OF ONE-THIRD
TO MARTIN M. WOLD, OF SAME PLACE.

LIQUID-MEASURE.

SPECIFICATION forming part of Letters Patent No. 469,805, dated March 1, 1892.

Application filed April 27, 1891. Serial No. 390,531. (No model.)

To all whom it may concern:

Be it known that I, JOHN J. HOVE, a citizen of the United States, residing at Minneapolis, in the county of Hennepin and State of Minnesota, have invented certain new and useful Improvements in Liquid-Measures; and I do hereby declare the following to be a full, clear, and exact description of the invention, such as will enable others skilled in the art to which it appertains to make and use the same.

My invention has for its object to provide a liquid-measure capable of ready application to a barrel, tank, or other reservoir, and adapted to discharge therefrom any one of several different measures of liquid. To this end I provide a receptacle capable of holding the largest desired measure—as, for example, a gallon—and subdivide the same by partitions into several different compartments of different capacities, corresponding to the ordinary denominations of liquid-measure, as the pint, quart, and half-gallon. In the receptacle, preferably near the bottom of the same, I place an inlet and outlet chamber having a discharge-spout extending to the exterior of the case, opening into the several different compartments, and a supply-pipe also extending to the exterior of the case and adapted for connection to the barrel or other reservoir. In this chamber is placed a valve for controlling the inlet and discharge of the liquid. At or near the top of the receptacle I provide an air-valve seat and air-valve having a pair of ports, one for the inlet of the air from the exterior of the case and the other for the exhaust of the same. From the exhaust-port a pipe is provided, also adapted for connection with the reservoir. The valves are preferably connected by a common shaft extending to the exterior of the case, and on the head of the shaft is placed a hand-lever for moving the valves. An indicator is also provided for locating the lever in the proper position to effect the necessary registration to discharge the liquid from any desired one or more of the compartments. The indicator is conveniently formed by extending the sides of the receptacles beyond the cap of the same and providing the extended flange with a series of notches, with which the hand-lever is made to engage to effect the proper registration. The hand-le-

ver is pivotally connected to the head of the shaft in order to permit this movement.

The invention is illustrated in the accompanying drawings, wherein, like letters referring to like parts throughout, Figure 1 is a vertical central section through the entire device. Fig. 2 is a cross-section on the line X X' of Fig. 1. Fig. 3 is a cross-section on the line Y Y' of Fig. 1. Fig. 4 is a vertical section through the air-valve and its seat. Fig. 5 is a cross-section on the line X" X''' of Fig. 4. Fig. 6 is a cross-section on the line Y" Y''' of Fig. 4, and Fig. 7 is a plan view of the device.

A is the receptacle, shown as of cylindrical form.

B is the inlet and discharge chamber.

C is the air-valve seat.

D is a central tube or sleeve connecting the chamber B with the valve-seat C.

E are radial partitions extending from the central tube D to the walls of the receptacle, which, taken together with said tube and chamber B, serve to divide the receptacle into a series of compartments a a^2 a^4 , which are sub-divisions of a gallon, a representing a compartment having the capacity of a pint, a^2 that of a quart, and a^4 a half-gallon.

The chamber B is provided with openings b and b', leading to the different compartments, and with an outlet or discharge pipe b''. From the chamber B extends to the exterior of the receptacle the supply-pipe F. In the chamber B is the valve H, adapted to control the openings b from the various compartments to effect the discharge, and the open end of the pipe F to effect the admission of the liquid. The valve is so constructed that when turned to effect the discharge from any compartment it will close the inlet from the pipe. As shown, the openings to the different compartments are at a lower level than the open end of the pipe F. The valve H is cut away on one side, as shown at h, to register with the openings b, and at a higher level is cut away, as shown at h', to register with the open end of the pipe F and the opening b'.

K is the air-valve, located in the seat C. Inlet-ports K' extend from the valve K through the valve-seat for the admission of air from the exterior of the case, and outlet-

ports K" extend through the case and the valve to the air-pipe L, which is attached to the case and is adapted for connection with the reservoir.

5 M is the shaft connecting the valves K and H.

N is the hand-lever, pivotally connected to the head of the shaft M.

P is the extended flange, provided with the 10 notches p to co-operate with the hand-lever N to effect the registration.

The operation is as follows: The measure having been connected with the barrel, tank, or other reservoir through the pipes F and L 15 and the hand-lever brought into its normal position, the outlets from the various compartments and the discharge-spout b' will be closed and the supply-pipe be open at its lower end. The air-valve will also be in such 20 position that the air will pass back from the receptacle through the exhaust-ports K" into the tube L, and thence to the reservoir, the port K' being closed. In this position the receptacle will be filled, the air from the receptacle displacing the liquid in the reservoir. In the filling the largest compartment in the construction shown is filled first and the others from the overflow therefrom. When 25 it is desired to discharge a given measure, the hand-lever is turned and made to register 30 with the proper corresponding notch on the indicator or flange P. Referring to Fig. 7, if it be desired to draw off a pint, for example, the hand-lever will be turned toward the left, 35 and made to register with the first notch, which will open the third compartment toward the left, as shown in Figs. 2 and 3, leaving all the others closed. If the lever be turned to the second notch in Fig. 7, both the pint- 40 compartments will be opened, allowing a quart to be discharged; if to the third notch, both the pint and the quart compartments will be opened, discharging a half-gallon; if to the fourth notch, all the compartments will be 45 opened, discharging a gallon. If the lever be turned in the other direction to the first notch toward the right from its normal position, the half-gallon compartment and the quart-compartment will be opened, effecting the discharge of three-fourths of a gallon. When 50 the valve is turned to open any of the compartments to effect the discharge, the air-valve will also be turned, so as to close the port K" and open the port K', thus affording a free 55 inlet of air from the exterior of the case, giving atmospheric pressure to assist in effecting the discharge. Whenever the hand-lever is brought back to its initial or normal posi-

tion, all the discharged openings are closed, together with the air-inlet port K', and the 60 supply-pipe and the air-exhaust ports K" are open and the receptacle is again filled from the reservoir. It will, of course, be understood that any form of valves and any form 65 of indicator for noting the proper registrations might be employed. It is also obvious that the measure is capable of use independent of any pipes for connecting the same with a liquid-reservoir. It was, however, primarily designed for use in connection with barrels 70 or tanks which ordinarily remain in a fixed position until all their contents are withdrawn. It is especially serviceable for measuring out vinegar, cider, and similar liquids.

What I claim, and desire to secure by Letters Patent, is as follows:

1. A liquid-measure comprising a receptacle, a liquid-supply pipe, and an air-exhaust pipe adapted for connecting the receptacle with a barrel, tank, or other reservoir, and 80 valves for controlling the inlet and outlet of the liquid and the air, the said valves being so arranged that when the liquid-valve is set for discharge the air-valve is set for admission, and when the liquid-valve is set for admission 85 the air-valve is set to close the air-inlet port and open the exhaust into said air-pipe and reservoir.

2. A liquid-measure comprising a receptacle divided into compartments of different capacity, a combined inlet and discharge chamber in communication therewith, having a supply-pipe adapted for connection with the reservoir, a valve in said chamber, an air-valve seat and an air-valve therein provided 90 with inlet and exhaust ports, a pipe from the exhaust-port adapted for connection to the reservoir, a common stem or shaft connecting 95 said valves, a hand-lever carried by said shaft, and an indicator for locating the lever, 100 as required, for the proper registration of said valves, substantially as described.

3. The combination, with the receptacle A, of the combined inlet and discharge chamber B, the valve-seat C, the central tube D, 105 the partitions E, the supply-pipe F, the valves H and K, the exhaust-pipe L, the hand-lever M, the notched flange P, and the discharge-pipes p', substantially as described.

In testimony whereof I affix my signature in presence of two witnesses.

JOHN J. HOVE.
